DISPENSING APPARATUS

Filed April 1, 1927

UNITED STATES PATENT OFFICE

ALBERT R. WHITE, OF CLEVELAND, OHIO, ASSIGNOR TO GLASCOCK BROTHERS MANUFACTURING COMPANY, OF MUNCIE, INDIANA, A CORPORATION OF INDIANA

DISPENSING APPARATUS

Application filed April 1, 1927. Serial No. 180,164.

My invention relates to dispensing apparatuses generally and particularly to apparatuses having temperature changing means and dispensing means.

5 One of the objects of my invention is to provide a simple and inexpensive and economically and easily and efficiently operable and sanitary dispensing apparatus.

Another object of my invention is to provide a dispensing apparatus with an efficient 10 temperature changing means.

Another object of my invention is to provide a dispensing apparatus with an efficient means to insulate the temperature in 15 the apparatus against temperature outside of the apparatus.

Another object of my invention is to provide a dispensing apparatus with means to prevent articles from being inserted into the 20 apparatus in any but one definite way or manner or in an undesired way or manner.

Another object of my invention is to provide a dispensing apparatus with means to prevent articles from jamming in the apparatus while the articles are being conducted 25 or conveyed through the apparatus.

Another object of my invention is to provide a dispensing apparatus with means to store articles in one portion thereof and with 30 means to change the temperature of articles in another portion thereof.

Another object of my invention is to provide a dispensing apparatus with means to store articles in one portion thereof and with 35 means to change the temperature of articles in another portion thereof and with means to identify the articles and arranged so that the same identifies the articles in the storage means as well as the articles in the 40 temperature changing means.

Other objects will appear, or become apparent or obvious, or will suggest themselves, during the description of the apparatus 45 in the accompanying drawings.

In dispensing apparatuses of the kind herein described it is, generally, desirable that the temperature of the articles which are dispensed by or through the instrumentality 50 of the apparatus is different than the existing natural temperature; it is also desirable

to effect the temperature changes in the most economical manner; it is also desirable that a quantity of the articles to be dispensed are stored in a convenient place and handy for the operator to save time and expense in dispensing the articles; it is also desirable that the articles to be dispensed can be deposited in and conveyed through the temperature changing means in the most economical manner and without causing any jamming of the articles in the apparatus; it is also desirable that the articles to be dispensed should always be inserted and leave the apparatus in a desirable way or manner; it is also desirable that the identification of stored articles as well as of articles under temperature change can be made easily and quickly; it is also desirable that such an apparatus can be cleaned easily for sanitary reasons; and it is also desirable that differently sized articles 55 60 65 70 can be handled by such an apparatus.

My invention aims to provide the necessary means to attain these desirable features as well as others as will appear presently in this specification and as illustrated in the accompanying drawings and as will suggest themselves from this description and illustration.

In order to illustrate my invention, for a full understanding thereof, I have selected and shown in the accompanying drawings 75 one particular apparatus embodying the features of my invention; I am aware, however, that my invention can be embodied in apparatuses of different designs.

In the accompanying drawings:—

Fig. 1 is a general perspective view of a dispensing apparatus embodying the features of my invention and having means for storing and cooling and dispensing bottles and bottle-like articles either of the same or

of different sizes and means for preventing articles from being inserted into the apparatus in an undesirable manner and means for preventing the jamming of articles in the apparatus and means for preventing the 80 85 90 95 radiation of the temperature of the apparatus.

Fig. 2 is a section of Fig. 1, on a larger scale, taken in a vertical plane indicated by 100

the line 2—2 in Fig. 1 and shows the relations of the interior parts more clearly.

Fig. 3 is a sectional view taken in a horizontal plane indicated by the line 3 in Fig. 2 and shows the relations between the walls and the partitions and the spacer and the feeders more clearly.

Fig. 4 is a sectional view taken in a horizontal plane indicated by the line 4 in Fig. 2 and shows the relations between the walls and the partitions and the pan more clearly.

Fig. 5 is a perspective view of one of the feeders with the abutment bar therein.

Fig. 6 is a plan view of Fig. 1 with the cover and the feeders removed.

Fig. 7 is a section taken in a horizontal plane indicated by the line 7—7 in Fig. 2 and shows the lower refrigerating chamber and the storage chambers more clearly.

Similar reference characters refer to similar parts throughout the views.

The apparatus shown in the drawings comprises, principally, the base unit A, the receptacle unit B with the cover C, the pan unit D, and the feeders E.

It is observed that all of the elements are made and formed of sheet material to insure economy in structure and lightness in weight to facilitate shipping and moving as well as the handling of the elements for cleaning or other purposes. The outside of the apparatus may be painted or plated or in any other manner made pleasing in appearance or to preserve the material or to afford easy cleaning. The inside of the apparatus may be painted or plated or otherwise prepared to prevent corrosion or other detrimental effects. The entire apparatus or the inner parts thereof may be made of any suitable material which resists corrosion or other detrimental effects which may occur or arise in any particular apparatus or in general apparatuses.

The base A has the two flat walls 10 and the two curved walls 11 joined together.

The upper portion of each of the curved walls 11 is formed with the seat 12 which, in the present instance, is not only arcuate but defines a portion of a true circle the center of which is located above the top of the base A. The flanges 13 are bent outwardly from the upper end of the walls 10 and 11 to abut the cover C.

In the present instance, four storage chambers 14 are provided in each of the walls 10 and ten storage chambers 15 are provided in each of the walls 11; all of the chambers are open on the outside of the apparatus and extend inwardly from the walls and are defined inwardly by the walls 16 which define or form the chamber 17 within the lower part of the base A.

The receptacle C has the two flat end walls 18 joined by the curved wall 19. In the present instance, the curvature of the wall 19 cor-

responds to the curvature of the seat 12 in the base A and the wall 19 is of the same curvature throughout the entire length thereof; this curvature being truly circular in the present instance. Other forms of curvature, or a combination of flat portions, or a combination of flat and curved portions can be used with equally good results. When other forms are used for the wall 19, the seat 12 is modified to correspond or to meet or to be adaptable to the particular form used.

Inside of the walls 18 and spaced therefrom and substantially parallel therewith are the two walls 20 joined by the wall 21 inside of and spaced from and substantially parallel with the wall 19.

The spaces between the walls 18 and 20 and 19 and 21 are filled with insulating material to retain the temperature in the apparatus. I have found that alternate layers of felt paper and fibre of sugar cane provides a good insulation means. To augment the insulation, I also provide the nipple and valve means 22 which permits a suction pump to be attached thereto to extract air from the spaces between the walls and which has valve means to prevent air from entering these spaces after some of the air has been extracted from them.

The partitions 23 divide the inside of the receptacle into ten channels 24 corresponding positionally to the ten chambers 15 in the walls 11. The outer edges of the partitions contact the inner surface of the wall 21 and the inner edges of the partitions are of true circular form in the present instance. The inner edges of the partitions may be made of any other than the truly circular form shown. The outer edges of the partitions may be made to conform or correspond to other forms of the wall 21. The depth of the partitions, and consequently the depth of the channels 24 is sufficient to permit the largest size bottle or other bottle-like article to pass longitudinally through the channels.

The two spacers 25 extend across the upper ends of the partitions and contact the inner edges thereof to retain the partitions in position. Each spacer has the flange 26 on the upper end thereof and the flange 27 on the lower end thereof; both flanges extending inwardly.

The pan unit D is made of one sheet of material in the present instance bent into true circular form corresponding to the true circular contour of the inner edges of the partitions and having the longitudinal edges or ends bent inwardly to form the flanges 28. The wall 29 of the pan has the perforations 30. There are no end walls on the pan.

Each of the feeders E is tubular in form and has the wall 31 beveled off at the bottom as shown. The slot or notch 32 extends part way into or through the shorter side of the wall 31 and is inclined or at an angle with the axes of the feeder. The pin or bar 33, a round

piece of material in the present instance, normally rests or lies in the notch 32 and can move laterally therein and normally rests in the lower portion of the notch due to the gravity thereof. The upper end of each of the feeders is fixed in the cover C and extends into the corresponding of the channels 24. As an alternative, the feeders can be fixed in the channels when so desired.

10 The wall of the cover C has the depressed portion 34, the flat portions 35, the curved portions 36, and the angular or bead-like portions 37 which form an ornamentation as well as a rest means for the cover on the flanges 15 13. The plate 38 extends over the depressed portion 34 to confine the insulation material 39 in the cover. The insulating material in the cover is of the same nature as the insulation material described above. The portions 20 35 have openings suitable either to receive the upper ends of the feeders or to permit articles to pass through them. These openings are spaced in accordance with the spacing of the channels 24. The cover may, conveniently, be hinged onto the receptacle by means 25 of the hinge element 40 within the portion 37 on one side of the apparatus, preferably on the back thereof. It is not necessary that the cover is hinged since it can be lifted off 30 bodily. When the cover is hinged or otherwise attached to the receptacle, the cover and the receptacle form a unit complete in itself with all of the parts thereof mechanically attached to each other.

35 The lids 41 are hinged to the plate 38 to normally close the openings in the portions 35 of the cover or the upper ends of the feeders as the case may be.

40 Since the present apparatus is designed to cool articles, the receptacle is filled with water up to the level 42 which is located above the flanges 27. For cooling purposes I use the ice 43 immersed in the water within the pan D. The overflow pipe 44 may be connected 45 to any suitable drainage means.

The diametrical size of the feeders is made sufficiently large so that the diametrically largest size article which is to be handled by the apparatus can easily pass through the same. The cross-sectional size of the channels 24 is made so that the largest articles which are handled by the apparatus can pass freely through the same in the arcuate path imposed by the arcuate structure of the receptacle elements.

55 The pan D normally rests on the inner edges of the partitions and the flanges 28 thereof abut the under side of the flanges 27 to hold the pan in position in the receptacle.

60 Since there are no end walls on the pan, the upper ends of the pan can easily be forced inwardly or toward each other and out from under the flanges 27 whereupon the pan can be removed from the receptacle through the top thereof for cleaning or other purposes.

The water in the receptacle is cooled by the ice therein and the level of the water is at the same height in all of the channels and in the interior of the receptacle. Since the level of the water is located above the junction of the pan on the flanges at the lower end of the spacers, temperature from the receptacle can not escape through the feeders when the lids are opened. The portions 35 of the cover C rest on the flanges 26 and the portion 34 of the cover extends downwardly and adjacent to the flanges 26 and thereby prevents escape of temperature from the receptacle. The seal between the cover and the receptacle and the water seal mentioned constitute an effective means to prevent the escape of cold air from the receptacle.

70 As a further aid to promote the insulation of the apparatus, the insulation material 45 is provided on the bottom of the chamber 17. As a further aid to promote the insulation of the apparatus, a suction pump can be attached to the nipple 22 to extract air from the spaces between the double walls.

75 A refrigerator means, mechanical, electrical or otherwise, can be installed in the chamber 17. Instead of the ice in the pan or the refrigeration means in the chamber 17 as described in the cooling apparatus shown, other temperature changing means can be used; 80 for instance, hot water or steam can be used when a heating apparatus is to be designed.

85 The apparatus shown and described has a base unit and a receptacle unit and a pan unit. The pan unit can be removed from the receptacle unit without disturbing the base unit or the receptacle unit in any manner and the receptacle unit can be removed from the base unit without disturbing the base unit or the pan unit in any manner. Neither one of the units is rigidly fastened to another unit; 90 and all units are individually removable from the apparatus. This arrangement facilitates the cleaning of the apparatus so that the same can easily be kept in most sanitary condition.

100 Each of the identification holders is in vertical alignment with one of the channels 24 and with one of the storage chambers 15. Each of the holders contains a card which identifies a certain brand of articles as illustrated by the letter "X" on one of the cards for instance. Articles of the brand "X" are stored in the chamber 15 which is in vertical alignment with the tag or card "X" and articles of the brand "X" are pushed into the 105 channel 24 which is in vertical alignment with the tag or card "X" and the channel is filled completely with these articles. While these articles are reposing in the channels, the temperature changing means, in the present instance the ice for cooling purposes, 110 changes the temperature of the articles in the channels to the temperature of the temperature changing means.

115 Now, when it is desired to dispense a cer-

tain brand of article, take one of those articles from the chamber 15 in which these articles are stored and push it into the opening or entrance portion of the channel which is in vertical alignment with that chamber and with that particular tag or identification card.

When this particular article, as the article 46 comprising a bottle for instance, is inserted neck first into the feeder in that particular channel, the neck portion thereof pushes the pin 33 laterally and upwardly in the notch 32 and out of the way of the bottle and thereby permits the bottle to be inserted into the channel as well as to be inserted in the proper direction. If attempt is made to insert the bottle with the bottom first, the bottom of the bottle, which has no tapering or neck portion, abuts directly against the pin 33 and, due to the inclination of the notch 32 and the gravity of the pin, retains the pin in its lowest position and thereby prevents the pin from being displaced or pushed out of the way and thereby prevents the bottles from being inserted in any but the proper direction or manner.

While the bottle 46 is being pushed down into the feeder, the other bottles in that particular channel are moved longitudinally in their channel and when the bottle 46 is pushed into the feeder fully, or nearly so, the bottle at the other end of that channel is pushed out of that channel and automatically raises the lid on that side of the apparatus in case the operator did not raise it previously whereupon the operator merely takes this last bottle off of the top of the apparatus to dispense the same. The bottle, having been cooled during its repose in that channel, will always emerge from the channel in a proper manner; that is with the neck portion first.

While one of the bottles 46 is pushed into the channel, the other articles or bottles in that channel are pushed longitudinally forward in that channel and since that channel is of one direction longitudinally the path of the bottles is unvarying, or in other words, the path of the bottles is one directional and the bottles all move in one definite path throughout the travel thereof. Since the longitudinal path of the bottles is one directional, the lateral position of the bottles is not changed during the travel and each bottle contacts the adjacent bottles in the same manner throughout the path thereof. Since the lateral position of the bottles is not changed during the longitudinal travel thereof, the bottles do not jam in the channel.

When the longitudinal path of the bottles is not one directional or not unvarying, as a combination of a curved and a straight path for instance, the lateral position of the bottles must change when the path changes; therefore, an apparatus which has a changing path must limit its capacity to one par-

ticular size of article and confine that article in such a manner that the same can not be displaced laterally sufficiently far to jam another article.

Since the path of the articles is unvarying in my invention and the articles always contact each other in the same manner throughout the travel thereof, the possibility of jamming is eliminated and articles of various sizes can be handled by the apparatus.

The apparatus shown and described is economical of structure as well as of operation; the articles can not jam therein; the apparatus is insulated against temperature radiation; the unitary structure of the elements thereof affords easy and convenient assemblage of the apparatus as well as easy and convenient disassemblage for easy and convenient cleaning thereof to attain a sanitary apparatus; the various articles in the apparatus are identified by means on the outside of the apparatus so that the desired articles will always be dispensed without the necessity of inspecting the same; and the articles are always conveyed out of the apparatus with the desired end first to avoid the necessity of inspecting the articles and manipulating the same to present them with the proper end upwardly.

I am aware that my invention can be embodied in apparatuses other than the cooling-dispensing apparatus shown and described and that changes can be made in the structure as well as in the arrangement of the elements and members shown and described; therefore, without limiting myself to the precise application of my invention as shown and described nor to the precise structure and arrangement of the elements and members as shown and described, I claim:—

1. An apparatus of the character described including a feeder having a shell with a notch extending part way through the same, the bottom wall of said notch being inclined, and a rod normally resting in the lower end of said notch and laterally movable therein.

2. An apparatus of the character described including a feeder having a shell, and a laterally movable abutment member extending transversely into the same, said shell having an inclined plane on which said abutment rides.

3. An apparatus of the character described including a receptacle having a side wall of arcuate form, a plurality of partitions in said receptacle against said side wall, the inner edge of each of said partitions being arcuate, a spacer connecting the ends of said partitions, and a pan resting on said inner edges.

4. An apparatus of the character described including a receptacle having a side wall of arcuate form, a plurality of partitions in said receptacle against said side wall, the inner edge of each of said partitions being arcuate, and an open ended arcuate pan insertable into and removable from said receptacle through

the top thereof and restable on said inner edges.

5. An apparatus of the character described, including a substantially **U** shaped receptacle, a plurality of partition members in said receptacle co-operating with said receptacle to provide guiding channels, the inner edges of each of said partitions being arcuate, oppositely disposed abutments at the ends of
10 said partitions and a pan resting on said inner edges and having its ends engaging said abutments to maintain said pan in position.

6. An apparatus of the character described, including a substantially **U** shaped receptacle, a plurality of partition members in said receptacle co-operating with said receptacle to provide channels, the inner edge of each of
15 said partitions being arcuate, an arcuate pan resting on said inner edges and means engag-
20 ing the edges of said pan for maintaining the same in position.

7. An apparatus of the character de-
scribed, including a substantially **U** shaped
25 receptacle, a plurality of partition members
in said receptacle co-operating therewith to
provide guiding channels the inner edge of
each of said partitions being arcuate, an open
ended arcuate pan resting on said inner edges
30 and means for engaging the edges of said pan
and maintaining the same in position.

8. An apparatus of the character de-
scribed, including a substantially **U** shaped
35 receptacle, a plurality of partition members
in said receptacle co-operating therewith to
provide guiding channels the inner edge of
each of said partitions being arcuate, a pair
of stop members disposed at diametrically
40 opposite points on said guide members and a
pan resting on said inner edges and having
its ends engaging beneath said stop mem-
bers.

In testimony of the foregoing I affix my
signature.

ALBERT R. WHITE.
